Primary Examiner — Paula Allen Greene*(74) Attorney, Agent, or Firm* — Jose Cherson Weissbrot(57) **CLAIM**

The ornamental design for a wireless headset charging box, as shown and described.

DESCRIPTION

FIG. 1 is a front elevation view of a wireless headset charging box showing our new design;

FIG. 2 is a rear elevation view thereof;

FIG. 3 is a left side view thereof;

FIG. 4 is a right side view thereof;

FIG. 5 is a top view thereof;

FIG. 6 is a bottom view thereof;

FIG. 7 is a front perspective view thereof;

FIG. 8 is a rear perspective view hereof;

FIG. 9 is a top view in an open configuration; and,

The broken lines depict portions of the wireless headset charging box that form no part of the claimed design.

1 Claim, 10 Drawing Sheets(56)
